US00D955479S

(12) **United States Design Patent** (10) Patent No.: **US D955,479 S**
(45) Date of Patent: **** Jun. 21, 2022**

(54) **DISPLAY FIXTURE**

- (71) Applicant: **TARGET BRANDS, INC.**, Minneapolis, MN (US)
- (72) Inventors: **David J. Rodkewich**, Saint Paul, MN (US); **Dan Smith**, Minneapolis, MN (US); **Kelly O'Halloran**, Minneapolis, MN (US)
- (73) Assignee: **Target Brands, Inc.**, Minneapolis, MN (US)
- (**) Term: **15 Years**
- (21) Appl. No.: **29/771,000**
- (22) Filed: **Feb. 18, 2021**

Related U.S. Application Data

- (60) Continuation of application No. 29/766,493, filed on Jan. 15, 2021, now Pat. No. Des. 942,545, which is a division of application No. 29/688,022, filed on Apr. 17, 2019, now abandoned.
- (51) **LOC (13) Cl.** **20-02**

(57) **CLAIM**

The ornamental design for a display fixture, as shown and described.

DESCRIPTION

FIG. 1 is a top and front perspective view of a display fixture showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the broken lines depict unclaimed subject matter only and form no part of the claimed design. The features shown in long dash-short dash bolded broken lines indicate the bounds of the claimed design and otherwise form no part of the claimed design.

1 Claim, 6 Drawing Sheets
